CLAIM

The ornamental design for a viewer apparatus, as shown and described.

DESCRIPTION

FIG. 1 is a top rear left perspective view of the viewer apparatus of the instant invention;

FIG. 2 is a bottom rear right perspective view thereof;

FIG. 3 is an enlarged front elevational view thereof;

FIG. 4 is an enlarged rear elevational view thereof;

FIG. 5 is an enlarged left side view thereof;

FIG. 6 is an enlarged right side view thereof;

FIG. 7 is an enlarged top view thereof;

FIG. 8 is an enlarged bottom view thereof;

FIG. 9 is a top rear left perspective view of the viewer apparatus of the instant invention in a second embodiment;

FIG. 10 is a bottom rear right perspective view thereof;

FIG. 11 is an enlarged front elevational view thereof;

FIG. 12 is an enlarged rear elevational view thereof;

FIG. 13 is an enlarged top view thereof;

FIG. 14 is an enlarged bottom view thereof;

FIG. 15 is an enlarged left side view thereof; and,

FIG. 16 is an enlarged right side view thereof.

The broken lines shown are included for the purpose of illustrating portions of the article that form no part of the claimed design.
